UNITED STATES PATENT OFFICE.

HARRY S. APPLEGATE, OF PASADENA, CALIFORNIA.

FOLDING CHAIR.

1,301,635.

Specification of Letters Patent. Patented Apr. 22, 1919.

Application filed April 13, 1918. Serial No. 228,436.

To all whom it may concern:

Be it known that I, HARRY S. APPLEGATE, a citizen of the United States, residing at Pasadena, in the county of Los Angeles and 5 State of California, have invented new and useful Improvements in Folding Chairs, of which the following is a specification.

This invention relates to chairs and the primary object of the invention is to provide a folding article of furniture of this character which is so constructed that when folded the weight of the seat of the chair will act in opposition to the unfolding of the chair irrespective of the position in 15 which the chair may be carried or placed.

Another object of the invention is to provide a chair of this character which is so constructed that when folded a frame comprising the front legs of the chair and a 20 seat will lie wholly within a frame which constitutes the chair back and the rear legs of the chair.

With these and other objects in view the invention resides in the novel combination 25 and arrangement of parts which will be hereinafter described and claimed.

The preferred embodiment of the invention has been illustrated in the accompanying drawing, although no restriction is necessarily made to the precise details of construction therein shown, as changes, alterations and modifications within the scope of the claim may be resorted to if desired.

In the drawing:—

35 Fig. 1 is a perspective view of a chair constructed in accordance with the invention.

Fig. 2 is a plan view of the chair and showing the same folded.

40 Fig. 3 is a longitudinal section through Fig. 2.

Fig. 4 is a cross section on the line 4—4 of Fig. 2.

Like characters of reference denote the 45 corresponding parts throughout the various views in the drawing.

Referring now to the drawing in detail the letter A designates a chair constructed in accordance with the invention and including a frame 5 which provides the rear legs and back of the chair.

The frame 5 may be formed from any material suitable for the purpose and includes side rails 6 and 7 which are braced 55 by crossed bars 8 disposed between cross strips 9 and 10 connected with the side rails

of the frame. The cross strips 10 are preferably two in number and coact with the rails 6 and 7 in providing the chair A with a back.

A seat frame 11 extends between the side rails 6 and 7 and is pivotally connected with these rails adjacent the lower of the cross strips 10, so that the frame 11 may be swung upwardly to lie between the side rails 6 and 7 and against the cross strip 10. The side bars of the seat frame 11 are of sufficient length to extend beneath and contact with the lower cross strips 10 when the seat frame is in a horizontal position, thus enabling 70 the frame 5 to limit the extent to which the seat frame 11 may be moved in a downward direction.

A second frame 12 which serves as the front leg of the chair A has the side rails 75 thereof arranged to extend at their upper ends within the frame 11, to which the side rails of the frame 12 are pivotally connected. A pair of brace bars 13 are pivotally connected at one end with the frame 12 80 and extend within the frame 5 to the side rails of which, the bars 13 are pivotally connected.

To the above described manner of connecting and arranging the frame 12, the 85 brace bars 13 and the seat 11 with relation to the frame 5 it will be apparent with reference to the drawing that when the chair is folded, the frame 11, frame 12 and brace bars 13 will lie wholly within the frame 5. 90

With reference to the drawing it will be seen that by so constructing the chair the above mentioned parts lie wholly within the frame 5 when the chair is folded, and the weight of the seat frame 11 will act in opposition to the unfolding of the chair when the same is carried in a vertical position, due to the fact that the downward movement of the seat frame will force the lower end of the frame 12 against the frame 5 and thus 100 prevent further movement of the parts.

Formed in the lower rail of the frame 12 is a recess 14 in which the fingers may be inserted to swing the frames 12 and 11 from within the frame 5 when the chair is folded. 105 Each of the frames 5 and 12 have fixed to the side rails thereof spurs 15 which prevent movement of the chair.

From the foregoing description taken in connection with the accompanying drawing, 110 it is apparent that an inexpensive and durable foldable chair has been provided which

is so constructed that when folded the weight of the seat of the chair will act in opposition to the unfolding thereof.

Having thus described the invention what 5 is claimed as new is:

A folding chair comprising a back frame, consisting of vertical members and cross pieces connecting said members together, a seat frame pivoted to said vertical members 10 and adapted to be swung upwardly between said members, said seat frame having its side members projecting rearwardly and contacting with one of the cross pieces when the seat frame is swung downwardly, a front

frame pivoted in the front end of the seat 15 frame and fitting in said frame when the chair is folded, with its lower end contacting with some of the cross pieces of the back frame to hold the chair in folded position, said lower end having a cut out portion to form a finger hold for unfolding the chair, braces pivotally connected with the lower part of said front frame and clamping bolts connecting the rear ends of said braces to the lower ends of the vertical 20 25 members of the back frame.

In testimony whereof I affix my signature.

HARRY S. APPLEGATE.
